UNITED STATES PATENT OFFICE.

EVERETT H. DUNBAR, OF LYNN, MASSACHUSETTS.

INSTEP-ARCH SUPPORTER.

No. 814,027.

Specification of Letters Patent.

Patented March 2, 1909.

Application filed December 8, 1908. Serial No. 465,817.

To all whom it may concern:

Be it known that I, EVERETT H. DUNBAR, of Lynn, in the county of Essex and State of Massachusetts, have invented certain new and useful Improvements in Instep-Arch Supporters, of which the following is a specification.

This invention relates to instep arch supporters adapted to be inserted in boots and shoes to afford such support for the instep arch of the wearer's foot as may be required by peculiarities and weaknesses of the foot.

The invention has for its object to provide simple and convenient means for regulating the height of the foot-supporting surface, particularly at the arched inner edge of the supporter, and it consists in the improvements which I will now proceed to describe and claim.

Of the accompanying drawings, forming a part of this specification,—Figure 1 represents a view of the under side of an instep arch supporter embodying my invention. Fig. 2 represents an edge view looking toward the inner edge of the supporter. Fig. 3 represents a section on line 3—3 of Fig. 1. Fig. 4 represents a perspective view of the shell portion of the reinforcing member, hereinafter referred to. Fig. 5 represents a section on line 3—3 of Fig. 1, the reinforcing member being removed.

The same reference characters indicate the same parts in all the figures.

In the drawings, 12 represents the metal base plate of an instep arch supporter, said base plate having its inner edge raised to form an instep supporting arch 13.

14 represents a pad of sole leather or other suitable flexible material bearing on the upper side of the base plate 12, and attached thereto at its end portions by rivets 15, the base plate and pad being separable from each other between the rivets. The pad normally conforms closely to the upper surface of the base plate so that a portion of one edge of the pad is held in an elevated position by the arch 13, and constitutes an extension of the arch.

In carrying out my invention, I provide an adjusting member which is removably inserted between the separable portions of the base plate and pad to give the corresponding portion of the pad any desired degree of elevation greater than that imparted to it by the base plate, the said adjusting member being variable as to its thickness, and therefore

as to the degree of elevation which it imparts to the pad. In this embodiment of the invention, the adjusting member is composed of two resilient sheet metal side pieces 16, 17, 60 connected at one end by a neck 18, the whole being preferably formed of a single piece which is bent to form the neck. The side pieces 16 and 17 form the sides of a shell in which is inserted a filler or cushion 19 which is preferably of compressible material, such as felt or rubber. The adjusting member is inserted between the base plate and pad between the points where said parts are connected by the rivets 15, and serves to elevate 65 the portion of the pad which bears upon it, the extent of elevation depending upon the thickness of the filler 19. It will be seen, therefore, that any desired elevation of the pad at a point between its points of attachment to the base plate may be effected, the degree of elevation being regulable by varying the thickness of the cushion, which can be readily inserted between and removed from the side pieces 16 and 17. To prevent 70 displacement of the cushion after its insertion between said side pieces, I may roughen one or both of the side pieces, preferably by indenting its outer surface, as indicated at 20, to form inwardly projecting bosses or 75 spurs which indent the compressible material of the cushion.

The external surfaces of the side pieces 16 and 17 are shaped to conform closely to the surfaces of the base plate and the pad on 80 which they bear, so that when the adjusting member is interposed between the pad and base plate, it will be confined in place by frictional contact between the contacting surfaces of the side pieces and the pad and 85 base plate.

The neck 18 may be provided with a downwardly projecting lip 21 adapted to abut against one edge of the base plate, as indicated in Fig. 3, and prevent the adjusting member from swinging or moving endwise between the pad and base plate. When only a minimum elevation of the arched edge of the supporter is desired, the adjusting member may be removed, leaving the supporter 95 in the condition represented in Fig. 5, all parts of the pad bearing on the base plate.

The side pieces 16, neck 18, and cushion or filler 19, constitute a compressible adjusting member which is wedge-shaped, the neck 100 constituting the apex of the wedge. The wedge shape of the adjusting member and

the smooth resilient sides of its shell, shaped to conform to the surfaces of the base plate and pad, enable the member to be inserted between said parts with the minimum frictional resistance. The width of the adjusting member is much less than the distance between the rivets 15, so that the member is adjustable edgewise between said rivets and lengthwise of the supporter. The user is thus enabled to change the location of the adjusting member to a considerable extent.

I claim:

1. A wedge-shaped compressible adjusting member for an instep arch supporter, adapted to be inserted between the base plate and pad of such supporter, said member being composed of a shell of resilient sheet material having separable side pieces, and a connecting neck forming the apex of the wedge, and a filler removably interposed between the sides of the shell.
2. A wedge-shaped adjusting member for an instep arch supporter, adapted to be inserted between the base plate and pad of such supporter, said member including two resilient sheet metal side pieces shaped to conform to the portions of the arch supporter

between which the member is inserted, and connected at one end by a neck which forms the apex of the wedge, and a removable filler interposed between the side pieces.

3. An adjusting member for an instep arch supporter, adapted to be inserted between the base plate and pad of such supporter, said member including two side pieces and a connecting neck having a lip adapted to bear against one edge of the base plate.

4. An adjusting member for an instep arch supporter, adapted to be inserted between the base plate and pad of such supporter, said member including two side pieces shaped to conform to the portions of the arch supporter between which the member is inserted, and a removable filler interposed between the side pieces, one of the side pieces being roughened to engage said filler and prevent its displacement.

In testimony whereof I have affixed my signature, in presence of two witnesses.

EVERETT H. DUNBAR.
